US0D1022491S

(12) **United States Design Patent** (10) **Patent No.:** **US D1,022,491 S**
(45) **Date of Patent:** **** Apr. 16, 2024**

(54) **COMBINED MARINE VESSEL AND
CONVERTIBLE SEATING**

(71) Applicant: **Brunswick Corporation**, Mettawa, IL (US)

(72) Inventors: **Prasad Dhananjay Deole**, Winter Springs, FL (US); **Matthew P. Klausky**, Port Orange, FL (US); **Paul E. Olvera**, Edgewater, FL (US); **Zachary M. Handziak**, Columbia, TN (US)

(73) Assignee: **Brunswick Corporation**, Mettawa, IL (US)

(**) Term: **15 Years**

(21) Appl. No.: **29/797,837**

(22) Filed: **Jul. 2, 2021**

(51) LOC (14) Cl. **06-01**

(57) **CLAIM**

The ornamental design for a combined marine vessel and convertible seating, as shown and described.

DESCRIPTION

FIG. 1 is a port, stern side perspective view of our new design, with the convertible seating being in a seating position;

FIG. 2 is a starboard, stern side perspective view of our new design, with the convertible seating being in a seating position;

FIG. 3 is a starboard, bow side perspective view of our new design, with the convertible seating being in a seating position;

FIG. 4 is a top view of our new design, with the convertible seating being in a seating position;

FIG. 5 is a stern side view of our new design, with the convertible seating being in a the position;

FIG. 6 is a port side view of our new design, with the convertible seating being in a seating position;

FIG. 7 is a port, stern side perspective view of our new design, with the convertible seating being in an alternative position of use as a sunlounge; and,

FIG. 8 is a top view of our new design, with the convertible seating being in an alternative position of use as a sunlounge.

The broken lines in the figures illustrate portions of the marine vessel and convertible seating for the marine vessel that form no part of the claimed design.

1 Claim, 8 Drawing Sheets
